(57) **CLAIM**

The ornamental design for disk wheel for vehicle, as shown and described.

DESCRIPTION

FIG. 1 is a front view of a disk wheel for vehicle;

FIG. 2 is a rear view thereof;

FIG. 3 is a right-side view thereof;

FIG. 4 is a perspective view thereof, as seen from the top, front and left sides; and,

FIG. 5 is a cross-section view thereof along the line A—A of FIG. 1.

The disk wheel for vehicle is shown on an enlarged scale in FIG. 5.
